UNITED STATES PATENT OFFICE.

VINCENT BENDIX, OF CHICAGO, ILLINOIS.

STARTER.

1,258,302.

Specification of Letters Patent.

Patented Mar. 5, 1918.

Application filed March 15, 1916. Serial No. 84,463.

To all whom it may concern:

Be it known that I, VINCENT BENDIX, a citizen of the United States, residing at Chicago, in the county of Cook and State of Illinois, have invented certain new and useful Improvements in Starters, of which the following is a specification.

My invention relates to a starter for engines such as gas engines, and to that type of starter exemplified by my Patent No. 1,125,935. My invention concerns that part of a starting device known as a transmission or drive for transmitting the power of a prime mover such as an electric motor to some member of the engine to be started, such as its fly wheel. In my type of starter the drive includes a screw shaft operated by the prime mover either directly or indirectly, and having mounted thereon a driving member in the form of a pinion, adapted to engage or mesh with the fly wheel or other engine member for rotating the crank shaft thereof in the starting operation. The object of my invention is to improve the resilient driving connection between the prime mover and the screw shaft by providing a coiled spring of a formation especially adapted for its particular purposes and functions.

In drives of this type there is a possibility of the coils of the spring becoming displaced in the coiling action, that is when the power is being transmitted from the motor to the screw sleeve or shaft on which the driving pinion is mounted. In case of such displacement there will be a binding between the spring and associated parts as well as the possibility of a displaced coil dropping between two of such parts where movement is desired. It is therefore necessary to employ a spring whose coils will not thus become displaced and at the same time provide for free compression and expansion of such spring longitudinally. Speaking in general terms I have overcome the difficulties in question by providing a spring whose coils are elliptical in cross-section with the longer diameters at right angles to the axis of the coils of the spring.

In the drawings Figure 1 is a section of my transmission or drive embodying my invention and showing a part of the prime mover or shaft actuated thereby, and a part of the engine member such as the fly wheel; and Fig. 2 a perspective of the coiled spring.

Referring to the embodiment of my in-

vention as herein shown, the prime mover (not shown) which may be in the form of an electric motor, is adapted to actuate a driving shaft 1, either directly or indirectly, in the manner clearly shown in my patent aforesaid. Upon the inner portion of this shaft there is mounted a sleeve 2 which is free thereon, and also capable of some oscillation and longitudinal movement. This sleeve is provided exteriorly intermediate its length with screw-threads, on which is mounted to screw a pinion 3, having teeth adapted to mesh with corresponding teeth 4 on the fly wheel 5 of the engine. This sleeve has at its inner end a stop nut 6.

A resilient driving connection is provided between the shaft 1 and the sleeve 2, the same comprising a coiled spring 7, anchored at one end to the shaft and at the other end to the sleeve. According to the specific construction herein shown, a spring barrel 8 is arranged concentrically of the shaft 1 and held in place at the outer end thereof by means of a pin or bolt 9, which also forms the means for anchoring the outer end of the spring 7. The other end of the spring is anchored to a stud or bolt 10, screwing into the outer end of the sleeve 2. The sleeve and spring barrel are arranged in axial alignment but not in contact, inasmuch as a space 11 is left therebetween, in order that the sleeve may have a slight movement outwardly against the tension of the spring.

As shown in the drawings the coils of the spring are elliptical in cross-section, with the result that their longer diameters are presented in line with the stress due to the coiling action, thereby giving the greatest possible strength with a given amount of metal. Also this form of spring prevents displacement of any one or more of the coils which would have a tendency to bind upon the spring barrel, or to slip into the space 11 and prevent the end-wise movement above referred to. Furthermore this formation of spring provides a very free compression and expansion of the spring consistent with the great strength thereof with respect to the coiling action, it being understood that the power of the motor is transmitted through this spring to the screw sleeve or shaft. This form of spring provides the sufficient amount of strength for the objects in view, and at the same time permits of the closest possible distance between the anchoring bolts.

2

While I have herein shown and described my invention in connection with a certain construction of transmission or drive, yet it will be understood that it is not limited to 5 any specific construction, for instance, while I have herein shown the screw shaft as of the hollow or sleeve form, yet my invention is equally applicable to the construction employing the solid form of screw shaft as 10 shown, for instance, in my prior Patent No. 1,146,992, issued to me on July 20, 1915.

I claim:

1. For use in transmission mechanism in engine starting apparatus, a spring coöperating with such mechanism and forming a yielding driving connection therein in the line of transmission of power, said spring being of the coiled type and having its coils flattened in a direction at right angles to the 20 axis of the coil.

2. For use in transmission mechanism in engine starting apparatus, a spring coöperating with such mechanism and forming therein in the line of transmission of power 25 a driving connection having a yielding torsional action and a yielding longitudinal action, said spring being of the coiled type and having its coils flattened at right angles to the axis of the coil to provide the 30 strength for said torsional action and the resiliency for said longitudinal action.

3. For use in transmission mechanism in engine starting apparatus, a spring coöperating with such mechanism and forming a 35 yielding driving connection therein between different rotatable members of the transmission mechanism, said spring being of the coiled type and having its coils flattened in a direction at right angles to the axis of the 40 coil.

4. In engine starting apparatus, a transmission mechanism including two rotatable members, one of which has a longitudinal movement, and a yielding driving connection 45 between such members consisting of a coiled spring having its coils flattened in a direction at right angles to the axis of the coil and arranged for torsional and for extension and compression actions.

5. In engine starting apparatus, a transmission mechanism including a rotatable shaft, a driving member mounted thereon, and a yielding driving means for driving the shaft consisting of a coiled spring having 55 its coils flattened in a direction at right angles to the axis of the coil.

6. In engine starting apparatus, a transmission mechanism including a rotatable shaft, a driving member mounted thereon, and a yielding driving means for driving 60 the shaft consisting of a coiled spring con-

nected with and encircling the shaft and having its coils flattened in a direction at right angles to the axis of the coil.

7. In engine starting apparatus, a transmission mechanism including a rotatable shaft, a driving member mounted thereon, and a yielding driving means for driving the shaft consisting of a coiled spring having 65 its coils flattened in a direction at right angles to the axis of the coil, said shaft having a limited longitudinal movement against the tension of such spring.

8. The combination of a motor, a driving member, operating means between the 75 motor and driving member for causing automatic engagement of the motor with and disengagement of the same from a member of the engine to be started, said means including a resilient driving connection 80 consisting of a coiled spring, whose coils are flattened in a direction at right angles to the axis of the coil.

9. In transmission mechanism for an engine starter, the combination of a rotatable 85 screw shaft, a driving member mounted thereon for longitudinal movement thereon and rotary movement therewith, and a resilient driving connection for the screw shaft 90 consisting of a coil spring, whose coils are flattened in a direction at right angles to the axis of the coil.

10. In transmission mechanism for an engine starter, the combination of a rotatable 95 screw shaft, a driving member mounted thereon for longitudinal movement thereon and rotary movement therewith, and a resilient driving connection for the screw shaft 100 consisting of a coil spring whose coils are substantially elliptical in cross-section with the greater diameter at substantially right angles to the axis of the coil and to the axis of the screw shaft.

11. In transmission mechanism for an engine starter, the combination of a rotatable 105 screw shaft, a driving member mounted thereon for longitudinal movement thereon and rotary movement therewith, a driving shaft, a coil spring forming a resilient driving connection between the screw shaft and the driving shaft, anchoring bolts connected 110 with said shafts respectively, and adapted to secure the opposite ends of the spring, the coils of such spring being substantially elliptical in cross-section with the greater 115 diameter at right angles to the longitudinal axis of the coils.

VINCENT BENDIX.
